UNITED STATES PATENT OFFICE.

ULRICH KORNSTEIN, OF NEW YORK, N. Y., ASSIGNOR OF ONE-HALF TO JAMES S. FRIEDMAN, OF NEW YORK, N. Y.

DETACHABLE HEEL.

1,268,731.

Specification of Letters Patent.

Patented June 4, 1918.

Application filed June 22, 1917. Serial No. 176,308.

To all whom it may concern:

Be it known that I, ULRICH KORNSTEIN, a citizen of the United States, and a resident of the city of New York, in the county of New York and State of New York, have invented certain new and useful Improvements in Detachable Heels, of which the following is a specification.

The present invention relates to improvements in detachable heels for boots and shoes.

The main object of the present invention is to generally improve the construction of detachable heels, more particularly the means for interlocking detachably the heel with a boot or shoe.

Another object of the invention is to provide a simple, inexpensive and efficient device of the character described, that is of great strength and durability, and is adapted to be readily applied to a shoe and capable of being quickly removed therefrom when desired, whereby the heel section, if worn or otherwise injured, may be conveniently replaced.

A still further object of the invention is to produce a device of the type mentioned, which can be manufactured on a commercial scale, or, in other words, one which is not so difficult to make as to be beyond the reasonable cost of such an article.

With these and other objects in view, which will more fully appear as the nature of the invention is better understood, the same consists in the combination, arrangement, and construction of parts hereinafter described, pointed out in the appended claim, and illustrated in the accompanying drawings, it being understood that many changes may be made in the size and proportion of the several parts and details of construction within the scope of the appended claim without departing from the spirit or sacrificing any of the advantages of the invention.

One of the many possible embodiments of the invention is illustrated in the accompanying drawings, in which:

Figure 1 is a longitudinal vertical section taken through the heel portion of a shoe, provided with a heel embodying the improvements forming the subject matter of this application; Fig. 2 is a section taken on line 2-2 of Fig. 1; Fig. 3 is a bottom plan view of the heel portion of the shoe; Fig. 4 is a top plan view of the detachable heel;

Fig. 5 is a section similar to the one shown in Fig. 2 of a detail, on a larger scale; and Fig. 6 is a section similar to the one shown in Fig. 5 of a modified detail of construction.

In the drawings, the numeral 10 indicates a portion of the upper of a shoe, to which is attached, in the usual manner, a sole 11. To the heel portion of the shoe-sole is fastened by screws, or otherwise, a plate 12, made preferably of metal, and provided with a plurality of circular apertures 13, that are arranged on a circle. Into each of these apertures merges an arc-shaped slot 14, all of said slots being disposed on the circle on which the apertures are located. This plate is disposed within a recess 15 in the heel portion of the sole, its lower face 16 being flush with the lower face of the said heel portion. The front section of the plate 12 is provided with a downwardly projecting shoulder 17, for a purpose hereinafter to be described. In the sole 11 are furthermore formed cavities 13' in alignment with the apertures 13 and the slots 14.

The heel section of the shoe is denoted by the numeral 18, and comprises the heel 19 proper and a, preferably, metallic plate 20, that is disposed within a recess 21 in the upper face of the heel. The plates 12 and 20, are preferably of the same configuration, and abut against each other when the heel is fastened to the shoe (Figs. 1 and 2). From the plate 20 rises a plurality of studs 22, each of which is provided with a head 22', adapted to enter the apertures 13 in the plate 12. The front portion of the plate 20 is provided with an upwardly extending shoulder 23, to which leads an incline 24 on the said plate.

In applying the detachable heel section to the shoe, the heads 22' of the studs 22 are first seated in the apertures 13 in the plate 12 and in the cavities 13' registering therewith. These positions of the parts are shown in dotted lines in Fig. 3 of the drawings. After this, the heel section is given a turn in the direction of the arrow shown in Fig. 3 of the drawings as far as the slots 14 in the plate 12 will permit. By turning the heel section in the manner indicated, the shoulder 17 on the plate 12 rides up on the incline 24 on the plate 20, dropping then in front of the shoulder 23 on the last-named plate. The interlocking shoulders 17 and 23 prevent a rotation of the heel sec-

tion on the shoe, and the heads 22' of the studs 22 hold the same against vertical movement.

A modification of the plates on the heel portion of the shoe and on the heel section, respectively, is shown in Fig. 6 of the drawings, differing from the one above described in that the said shoulders are formed, for instance, by stamping in a manner that 10 those faces of the said plates which abut against the heel portion of the sole and the heel section, respectively, remain plane faces, thereby permitting the said plates to be attached to the elements mentioned without forming recesses therein to accommodate the projections on the said plates.

What I claim is:

The combination with the heel portion of a shoe-sole, of a plate fastened thereto having a plurality of apertures and an arc-

shaped slot merging into each aperture, a detachable heel section, a plate attached to said heel section provided with headed studs rising from its upper face, said studs being adapted to be inserted into said apertures 25 and to be seated in said slots when said heel is turned, after the insertion of the heads of said studs into said apertures, in the proper direction, and coating shoulders upon said plate and said heel section for preventing a 30 turning movement of said heel section on said plate when once brought into the proper position, the shoulders on each plate extending toward the other plate and being formed to leave the opposite face of the respective plate smooth.

Signed at New York, in the county of New York, and State of New York, this 13th day of June, A. D. 1917.

ULRICH KORNSTEIN.
